UNITED STATES PATENT OFFICE.

MARCUS A. ADLER, OF NEW YORK, N. Y.

SYSTEM OF EXHIBITING SAMPLES OF GARMENTS.

SPECIFICATION forming part of Letters Patent No. 538,761, dated May 7, 1895.

Application filed January 28, 1895. Serial No. 535,980. (No model.)

To all whom it may concern:

Be it known that I, MARCUS A. ADLER, a citizen of the United States, and a resident of New York city, in the county of New York and State of New York, have invented certain new and useful Improvements in Systems of Exhibiting Samples of Garments, of which the following is a specification.

The general object of my invention is to facilitate the carrying of samples of a coat or other similar garment, by commercial travelers or "drummers;" and especially samples of manufacturers' goods.

Prior to my invention it has been customary with commercial travelers, to carry either unmade samples of cloth, showing merely the pattern thereof, or half-sections of a garment, such as a coat, that is to say, a section equivalent to one half of a made-up coat.

The disadvantages attending these systems of carrying the samples are, as to the example first named, that the plain goods are not adapted to exhibit the appearance of a garment made therefrom; while, as to the use of the made-up half-sections of the garment, the samples involve a considerable waste of labor and material, since, on account of frequent handling, and consequent wear, the sample-sections are generally unfit for further use in a garment.

With a view to obviate these disadvantages, my invention consists in the employment of a series of parts, of cloth, each cut and finished to represent a profile of the front edge of the coat or other selected garment, the parts being superimposed, in symmetrical relation, and each being of a different or contrasting color or pattern from the other of the series.

In the accompanying drawings, Figure I represents a side view of an assemblage of parts constituting my sample. Fig. II represents one of the parts detached.

Similar letters of reference indicate similar parts.

The letter A indicates each of the parts composing the sample, each being cut and finished from a piece of the selected cloth, to represent the profile of the front edge of a coat, which, in this example, is what is known as a sack coat. As shown, each of the parts A is of a different or contrasting pattern from the other

or remaining parts; and in exhibiting the same, as a sample, the parts are superimposed or laid one upon the other, in symmetrical relation, so as to present, collectively, the 55 appearance of a series of whole coats; the boundary lines of the superimposed parts being substantially parallel to each other.

The outermost member of the superimposed parts A, may be extended to represent the 60 side of a coat, including the sleeve, as shown in Fig. I; and the parts may be provided, alternately, with a button and button hole, by means of which they may be connected together.

In defining the scope of my invention I would remark that I do not claim the sample composed of a flat half-section of a garment, nor one composed of pieces of cloth mounted on a card. Neither do I claim the representation of patterns of cloth in print, on a card; such being old, but

What I claim, and desire to secure by Letters Patent, is—

1. A series of dummy garment samples each 75 consisting of a narrow strip of goods finished at one edge to exhibit the profile cut of a garment and unfinished on the other edge, said samples being superimposed and provided with means whereby they may be readily attached and detached, and said samples being arranged so that their finished edges are free and exposed and their unfinished edges are concealed, substantially as set forth.

2. A series of dummy garment samples each 85 consisting of a narrow strip of goods finished at one edge to exhibit the profile cut of a garment and unfinished on the other edge, said dummy samples being superimposed and attached together near the front finished edges 90 thereof, but arranged so that said finished edges are free and exposed, while the unfinished edges are concealed, in combination with an outer sample applied to said dummies and finished to exhibit a whole side or 95 other extended portion of the garment, substantially as set forth, whereby the appearance of a series of whole samples is simulated.

3. A series of dummy garment samples each 100 consisting of a narrow strip of goods finished at one edge to exhibit the profile cut of a garment and unfinished on the other edge, said

dummy samples being superimposed so that their finished edges are free and exposed, in combination with an outer sample applied to said dummies and finished to exhibit a whole side or other extended portion of the garment, said outer sample having its profile edge arranged above and parallel with the profile edge of said dummy samples and concealing all unfinished edges thereof, all of said sam-

ples being provided with means whereby they may be readily attached together near their front edges, or detached when desired, substantially as set forth.

MARCUS A. ADLER.
